(57) **CLAIM**

The ornamental design for an electrical housing, as shown and described.

DESCRIPTION

FIG. 1 is a top left front perspective view of the electrical housing showing my new design;

FIG. 2 is a bottom plan view thereof;

FIG. 3 is a back elevational view thereof;

FIG. 4 is a left side elevational view thereof;

FIG. 5 is a front elevational view thereof;

FIG. 6 is a right side elevational view thereof; and,

FIG. 7 is a top plan view thereof.

The broken line portions of the figures are included to show unclaimed subject matter only and form no part of the claimed design.
